ABSTRACT

A machine for packing gramophone records in sleeves is arranged to feed two series of blanks, fold edge portions of the blanks of one series, deposit a record upon each of the latter blanks, and then unite the blanks of the two series in pairs to produce complete sleeves each enclosing a record. As described, the machine also includes means for presenting the records to inspection devices, for inserting each record in a bag before its deposit on a blank, and for check-weighing the completed sleeves.

PACKING MACHINES

This invention relates to machines for packing gramophone records of the conventional thin disc form (hereinafter for convenience termed "records") or like articles.

The accepted form of container in which records are packed is a so-called "sleeve," essentially comprising a square envelope of cardboard, most commonly without a closure flap (i.e. open along one edge). Recently there have been devised improved forms of sleeve in which at least one of the closed edges has a "spine," i.e. a narrow wall at right-angles to, and joining, the principal faces of the sleeve. Such spines may be provided only along the edge parallel to the open edge, or along all three closed edges, or (where a closure flap is provided) along all four edges, and tend to strengthen the sleeve, increase the protection given to a record placed in the sleeve, and provide a surface convenient for the printing of a title or other identifying matter which is desired to be visible when records are stored in sleeves disposed in the usual side-by-side arrangement on shelves. A sleeve with spines is commonly made from two blanks; examples of such sleeves are disclosed in British Specifications Nos. 943,285, 1,115,491 and 1,119,823, and also in U.S. Pat. No. 3,495,765 and U.S. Application Ser. No. 779,685, assigned to the same assignee as the present application.

Hitherto, the packing of records in sleeves has been largely done by manual insertion. It is an object of the present invention to provide a machine for packing records or like articles more economically than heretofore.

According to the invention, there is provided a packing machine for records or like articles, comprising first feed means for feeding a first series of sleeve blanks one at a time through an insertion zone to a uniting device, record feed means for depositing records one at a time in said insertion zone, said record feed means being arranged to operate in synchronism with said first feed means so that each record is deposited in said insertion zone at a time when a blank of said first series is in said insertion zone so as to be received upon said blank, and means for delivering sleeve blanks of a second series one at a time to said uniting device in synchronism with the arrival of the blanks of the first series therat, said uniting device being arranged to secure each blank of the second series to the simultaneously-arrived blank of the first series so as to form a complete sleeve enclosing the record previously deposited on the blank of the first series.

The blanks of the two series may be of such form as to form respectively the backs and fronts of complete sleeves and may be printed (before delivery to the machine embodying the invention) with such pictorial and/or other matter as desired. For convenience, the blanks of the first series will hereinafter be termed "back blanks" and the blanks of the second series "front blanks."

It is preferred that each back blank should be stationary in the insertion zone while the record is deposited upon it; for this purpose, the first feed means may comprise one conveyor which moves intermittently and is arranged to feed the back blanks to the insertion zone and another conveyor, preferably a continuously-running conveyor to carry the back blanks (each with a record thereon) from the insertion zone to the uniting device. Alternatively, the first feed means may comprise two continuously-running conveyors each having pushers for propelling the back blanks, one of said conveyors being arranged to deliver each blank to the insertion zone and the other to transport the blank (and record) from the insertion zone to the uniting device, the relative timing of the two conveyors being such that after each blank is pushed by the one conveyor on to a stationary surface in the insertion zone, the blank is allowed to remain stationary on said surface for a brief period before a pusher of the other conveyor engages the blank to propel it onward.

Preferably the back blank is provided with flaps along all four of its sides and the machine includes folder means for forming the flaps on three of said edges to provide spines and surfaces to which the front blank may be secured in the unit-

ing device, also to form the flap on the fourth edge to provide a spine and a closure flap. The machine conveniently has a supply hopper for accommodating a supply of back blanks, extractor means for removing the back blanks one at a time from said hopper, and an input conveyor on to which the extractor means delivers each blank as it is removed from the hopper, said input conveyor being arranged to transport the blanks past plough folders arranged to form the flaps on the edges (hereinafter termed "top" and "bottom" edges, the top edge being the edge with the closure flap) parallel to the direction of motion of said input conveyor. Thereafter, the flaps on the remaining two edges (termed "side" edges) require folding, and we prefer to arrange that after the folding of the top and bottom edges the attitude of the blank should be altered relative to its direction of travel, so that the top and bottom edges are thereafter at right-angles to said direction. It is preferred to accomplish this change of attitude by arranging the input conveyor at right-angles to one conveyor of the first feed means, so that on transfer from the input conveyor to said one conveyor each blank changes its direction of travel while the orientation of the blank relative to stationary parts of the machine remains unchanged, as this arrangement helps to make the machine compact in plan. However, if a machine of elongated form in plan is acceptable, said one conveyor of the first feed means may serve as the input conveyor, in which event means are provided for rotating each back blank through a right-angle after folding of the flaps on its top and bottom edges.

30 In the preferred arrangement having an input conveyor extending at right-angles to an intermittently-operating conveyor of the first feed means, the folders for the side edges are required to operate on each successive back blank while it is stationary and hence reciprocating folders are provided adjacent to the intermittently-moving conveyor of the first feed means.

The delivery means for the front blanks normally comprises a further supply hopper generally similar to that for the back blanks and also having extractor means for removing blanks 40 one at a time. Said further hopper may if desired be mounted close to the uniting device so that the extractor means delivers each blank direct to the latter. It is however preferred to provide a hopper for the front blanks close to that for the back blanks, with one or more conveyors so arranged that the feeding of front blanks and back blanks to the uniting device is synchronised, i.e. as each front blank is extracted from its hopper, a back blank is extracted from its hopper and these two blanks reach the uniting device simultaneously. While this arrangement may increase the cost of the machine, it has operating advantages in that the two hoppers are close together and loading of the hoppers can conveniently be done by a single operator and (more importantly) it is easier to ensure that individual front and back blanks which are to be united are properly matched; the need for matching arises from what is conveniently printed on the front and back of a record sleeve — both front and back normally carry the title and catalogue number of the record packed in the sleeve, this data being accompanied on the front by a picture and on the back by descriptive matter.

65 It is preferred to provide the machine with means for automatically checking that the records and sleeve blanks are properly matched, i.e. that pictorial and/or descriptive matter printed on each blank is pertinent to the record to be packed in the sleeve made by assembly of the blanks. For this purpose it is convenient to provide each blank with a coded marking readily sensed by reading means forming part of the machine; such reading means may for example be photo-electric or electro-magnetic, and the markings may be applied to parts of 70 the blanks which are concealed when the blanks are assembled into sleeves. Similarly the records may be marked, but at present we prefer to apply such markings to pallets on which the records are carried to the machine.

The checking of blanks and records may be arranged to influence the machine in various ways; so long as the markings

sensed on the blanks and records (or record pallets) are correctly matched, then clearly no disturbance of the machine's operation is necessary, but when a mismatch is sensed various results may be required, for example the machine may be stopped and a visual and/or audible alarm device may be energised. The arrangement at present preferred is that a coded identification of the record to be packed shall be fed into the checking means by manual operation of a control panel or keyboard, and that the checking means shall then, as machine operation proceeds, compare signals from the several reading means with a stored representation of said coded identification. If a signal from the reading means for either the first or second series of blanks, sensing the markings on such blanks as they are extracted from their supply hopper, gives a mismatch indication as a result of such comparison, then the checking means delivers a control signal which causes deflection of at least the relevant blank into a reject hopper; in practice it can be convenient to deflect both blanks to reject hoppers, as it is somewhat simpler than to preserve synchronism in feeding the two series of blanks.

Markings on record pallets may be sensed by reading means as the pallet is being moved into the machine, and if a mismatch is found upon comparison of a signal derived from this reading with the stored coded identification, then a control signal may be delivered to stop means in the path of the record pallet, to cause said stop means to prevent the record pallet from reaching an unloading station in the machine, so that the records on that pallet cannot be fed into the machine for packing. It is desirable in any event to provide for an audible or visible signal to be given whenever a mismatch is detected, so that an operator may be aware of any need to provide a fresh supply of blanks and/or records to permit normal operation of the machine to be resumed.

It is desirable, for obvious reasons, to ensure that every sleeve produced by a machine embodying the invention shall contain a record. In large part this may be accomplished by so arranging the record feed means that a stack of records is held adjacent to the insertion zone, one record being removed from this stack for deposition whenever the arrival in said insertion zone of a blank of the first series is sensed by a detector device. This stack of records adjacent to the insertion zone serves as a form of buffer store, and the record feed means is arranged to supply records to said stack at a rate greater than the rate of arrival of blanks in the insertion zone, further means being provided to sense the number of records in the stack and suspend supply of further records thereto whenever there is a desired maximum number of records in the stack. However, we prefer also to check that finished sleeves are correctly packed with one record each, and for this purpose the machine may include a weight checking device arranged to receive sleeves from the uniting device.

The preferred arrangement of the record feed means just described in outline allows an intermittent flow of records into the machine without interruption of its operation. This is advantageous as it is desirable to inspect records before they are packed; a proportion of records are liable to have surface defects or other faults, and they may be inspected, and faulty records rejected, before entering the machine. Preferably, however, the machine incorporates inspection equipment and the record feed means is arranged to present the records in succession to such equipment and to supply to the stack only those records in which no fault is found, diverting faulty records to a record reject hopper.

The recorder feed means may take various forms; it is preferred to arrange for the records to be received in stacks on pallets, one type of pallet used comprising a base generally in the form of a circular disc of diameter slightly larger than the records it is to carry, said base carrying at its center an upstanding vertical pillar of diameter to fit the center holes of the records. A stack conveniently contains 50 or 100 records and usually has metal supporting discs between adjacent records at regular intervals, e.g. 5 or 10 records apart; the record feed means desirably therefore includes means for detecting the

presence of such supporting discs and separating them from the records. Conveniently such detecting means may include an electronic metal proximity detector.

It is normal practice to enclose each record in a paper or plastics bag before placing it in the sleeve and the machine may include means for inserting each record into such a bag before it is deposited upon a blank in the insertion zone. Such means conveniently comprises a bag feed arranged to take bags singly from a hopper and convey each bag in succession to a position adjacent to the insertion zone where each bag encounters a bag opening device arranged to open the mouth of the bag while a record is fed therein. The opening device preferably is in the form of a pair of eccentric rollers, driven in phase so that as a leading edge of each bag enters between the rollers the surfaces of the latter are at their position of closest approach, while as the bag passes on between the rollers their surfaces separate. The bag is so orientated relative to the rollers that a side edge of the bag is the leading edge as the bag enters between the rollers, hence the top (open) edge of the bag passes between the rollers at one end; at this end, both rollers are provided with holes around their circumference, and a suction chamber associated with each roller applies suction to said holes as they pass adjacent to the other of said rollers, so that as each roller revolves, the holes confronting the other roller (and hence adjacent to the bag) at any instant are subjected to suction and the front and back of the bag are therefore held against the rollers by atmospheric pressure. Thus as the rollers revolve, and the separation between their confronting surfaces increases, the front and back of the bag are progressively moved apart. The record feed means is arranged to deliver a record between the rollers as they are at (or near) the position at which their confronting surfaces are most widely separated, the record moving parallel to the axes of the rollers, as it is delivered.

In order that the invention may be well understood, a preferred embodiment thereof will now be described referring to the accompanying drawings in which:

FIG. 1 is a diagram depicting, in perspective, the paths of sleeve blanks and records through a preferred form of machine embodying the invention.

FIG. 2 is a perspective view of the machine to which FIG. 1 is pertinent.

FIG. 3 is a perspective view of the blank feed hoppers, and adjacent parts.

FIG. 3A is a rear view of the feed device of FIG. 3, taken in the direction of arrow 'Z' of that figure and drawn to a larger scale.

FIG. 3B is a section taken on the line Y—Y of FIG. 3A.

FIG. 3C is a section taken on the line X—X of FIG. 3A.

FIG. 4 is a front view, partly in section, of apparatus for feeding records, one at a time, from the bottom of a stack,

FIG. 4A is a plan of FIG. 4, with some parts omitted for clarity,

FIG. 4B is an enlarged view of part of the apparatus shown in FIG. 4A taken on the line V—V of FIG. 4A,

FIGS. 4C, 4D, 4E and 4F show successive positions, during feeding of a record from the bottom of a stack, of parts of the apparatus of FIG. 4 drawn to a larger scale,

FIG. 5 is a sectional side view of apparatus for transferring a partly formed record sleeve from an intermittent to a continuously moving conveyor,

FIGS. 5A, 5B are views similar to FIG. 5 but the various parts are shown in different positions,

FIG. 5C is a plan view of the apparatus of FIG. 5,

FIG. 5D is a sectional view of a detail drawn to a larger scale,

FIG. 5E is a section on the line U—U of FIG. 5C, drawn to the scale of FIG. 5D,

FIG. 5F is a reproduction of part of FIG. 5 but on a larger scale,

FIG. 6 is a side view, partly in section, of apparatus for inverting and weighing a record sleeve containing a record,

FIG. 6A is a section on the line T—T of FIG. 6,

FIG. 6B is an end view of the apparatus taken in the direction of arrow 'S' of FIG. 6,

FIG. 6C is a section taken on the line R—R of FIG. 6 drawn to a larger scale,

FIG. 7 is a front elevation of apparatus for inserting a record into a bag,

FIG. 7A is a section taken on the line Q—Q of FIG. 7,

FIG. 7B is a plan view of FIG. 7A,

FIGS. 7C, 7D and 7E are diagrammatic views showing successive positions of certain parts during insertion of a record into a bag,

FIG. 8 is a diagrammatic side view of apparatus for feeding records, one at a time, from the top of a stack,

FIG. 8A is a plan view of part of the apparatus of FIG. 1, drawn to a larger scale, and showing extra detail,

FIG. 8B is a section on the line P—P of FIG. 8, but showing extra detail, and drawn to the same scale as FIG. 8A,

FIG. 8C is a view, partly in section and on a larger scale, of a detail of FIG. 8B,

FIGS. 8D, 8E and 8F show three successive stages in the separation of a record from the top of a stack,

FIG. 9 is a plan view of apparatus for transporting records past a succession of inspection devices,

FIG. 9A is a section taken on the line O—O of FIG. 9,

FIG. 9B is a section taken on the line N—N of FIG. 9,

FIG. 9C is a section taken on the line M—M of FIG. 9, and

FIG. 9D is a detail of FIG. 9B but with parts thereof shown in a different position.

Firstly there will be described the paths of movement of sleeve blanks and records through the machine, indicating the operations performed at various positions, with reference to FIG. 1.

As shown in FIG. 1, two stacks of sleeve blanks the stack provided, indicated by references 1 and 2. In the stack 1, the blanks as supplied to the machine are all creased, perforated, and printed with whatever is required to appear on the back of a finished sleeve and hence the blanks in this stack and fed therefrom will be referred to for convenience as "back blanks." For corresponding reasons, the blanks in and taken from the stack 2 will be referred to as "front blanks."

Blanks are fed from both stacks, in synchronism, one at a time along horizontal paths. The back blanks taken from stack 1 are fed somewhat downwards and the front blanks from stack 2 are fed somewhat upwards so that the path along which the latter blanks travel is at a higher level than the path along which the back blanks travel, the two paths being also laterally displaced as are the stacks 1, 2. As the back blanks are travelling continuously away from the stack 1, they are subjected to folding of their edge portions along the two edges which are parallel to their direction of movement. Thus a back blank which has just left the stack 1, as indicated by reference 3, will be seen to be lying flat while a blank which has travelled some distance further and indicated by reference 4 has its side edge portions folded. Just after completion of the desired folding operations on the side edge portions, each blank in turn reaches a position 5 at which it ceases to travel away from the stack 1 and is almost immediately caused to start moving intermittently at right angles to its previous direction of travel. As this intermittent movement proceeds, the edge portions of the blank which are now the side edges, relative to the blanks new direction of travel, are partially folded so that after travelling some distance in the new direction and reaching the position indicated by the reference 6 all four edges of each back blank have been at least partially folded. At this position 6, which is one of the positions at which the back blank stops momentarily in the course of its intermittent motion, a record enclosed in an inner bag is dropped on to the back blank. Continuing its intermittent motion, the back blank passes on to stop at a position 7; from position 7, the back blank is moved on continuously in the same direction to a position 8, folding of the side edge portions being completed as the back blank is moving between position 7 and position 8.

Returning to the consideration of front blanks fed from stack 2, these blanks follow a path generally similar to that of the back blanks, but undergo no folding operations. Thus the front blanks travel away from the stack 2, until they reach a position 9 at which each front blank stops momentarily and then again starts moving but in a direction at right angles to its former direction of motion. As each front blank moves away from the position 9, it is travelling horizontally in the same direction as back blanks leaving the position 5 (but moving continuously, not intermittently as are the back blanks in this region) and in a path vertically aligned with the path of back blanks leaving position 5, so that the front blanks pass over positions 5, 6 and 7. However, as each front blank passes through a position 10 above position 7 in the path of the back blanks it commences to descend obliquely so that the leading edge of each front blank meets the leading edge of a corresponding back blank as the latter comes to position 8. The two blanks then move together as a complete sleeve, adhesive on edge portions of the front blank serving to secure the back blank and the front blank together to form a complete sleeve. The adhesive is applied to side and bottom edge portions of the front blank as it descends obliquely from position 10, i.e. very shortly before encountering the back blank as the latter passes through position 8.

The complete sleeves thus successively formed, each containing a record, move on in the same direction to a position 11, then in an arcuate path as indicated at 12 (passing through a position at which the weight of each sleeve is checked), and 30 then move horizontally on to a buffer stack 13. From the stack 13, the completed record-containing sleeves are fed one at a time through positions 14, 15, 16 in sequence; at these last mentioned three positions an "overwrap" is applied and then 35 the completed sleeves are fed out on to a further stack 17 from which they may be removed in batches as required as indicated at 18.

Now returning to the position 6, it will be remembered that here a record, in an inner bag, was deposited upon each back blank. The records thus supplied enter the machine in stacks 40 on pallets as indicated by reference 19, being fed to a position 20. From here an operator (not shown) may as required place each stack in a feed-in position 21 and at this position records are removed, one at a time, from the top of the stack and fed 45 horizontally to a buffer store 22. The bottom record in the store 22 is allowed to descend slightly and then is moved in arcuate paths through positions 23, 24, 25, 26 and 27. At position 23, the surfaces of the record are cleaned and the record inspected for flatness and concentricity, and then at positions 24 and 26 the record is being subjected to further inspection, 50 first of one of its surfaces and then of the other. Providing that the results of such inspections are satisfactory, from the position 27 the record is fed horizontally into an inner bag indicated at 28 and then allowed to descend on to a buffer stack 29. This stack is held adjacent to the position 6 and it is the 55 bottom record of this stack which is deposited each time a back blank is stopped at the position 6.

The inner bags are fed horizontally from a supply position 30 to the position at which the bag 28 is shown, the bags 60 travelling below the path of front blanks leaving position 9 and above the path of back blanks leaving position 5.

Now, turning to FIG. 2 showing the machine in which the foregoing operations take place, it is noted that where possible the references used on FIG. 1 are also to be seen on FIG. 2. 65 Several of the parts of the machine shown in FIG. 2 are shown in detail in other figures and will be described later.

The machine shown comprises two feed hoppers 51, 52 containing the stacks 1, 2 respectively. In the hoppers 51, 52 the blanks lie in planes inclined slightly from the vertical (as best seen in FIG. 1) and each of said hoppers includes mechanism (not shown in detail in FIG. 2) for removing blanks one at a time from the underside or back of the stack. In the case of the hopper 51, each blank is removed by downward and rearward movement so as to emerge moving horizontally on to a horizontal conveyor belt 53. In the case of

the hopper 52, each blank is removed from the stack by upward movement and guided to emerge moving horizontally on to a horizontally-extending conveyor belt 54, at a higher level than the belt 53. The conveyor belts 53, 54 serve to carry the back blanks and front blanks respectively to the positions 5, 9. Said belts 53, 54 however terminate somewhat before said positions 5, 9 so that as blanks reach said position they have moved clear of said belts.

The machine being described is arranged to make finished sleeves of the type having a so-called "spine" along each of its four edges. By "spine" is meant a stiff shallow wall between the front and back panel of the sleeve, and in essence this is produced by first folding over an edge portion of the back blank and adhesively securing it to the next portion of the blank on to which it is pressed, and then again folding over the edge portion now of double thickness to form both the spine and a flap parallel to the main panel with which it is integral. As will have been noted from the above description of FIG. 1, in the present instance the spines are formed on the back blanks, the front blanks being substantially square and of the size of the finished sleeve. Said spines are formed as just indicated along three of the edges of the back blank, while along the fourth edge there is formed a spine and a closing flap which in the finished sleeve is not adhesively secured to the front blank but is tucked in; this spine and flap are of single thickness for greater flexibility. The edge of the blank and of the sleeve which has this closing flap will be referred to herein as the top edge, the opposite edge will be referred to as the bottom edge, and the remaining two edges will be termed side edges.

The back blanks are put in the hopper 51 with their top edges to the right as seen in FIG. 2. Accordingly, each back blank as it travels along the conveyor belt 53 still has its top edge to the right and its bottom edge to the left and these are the edges, parallel to the direction of motion of the blank at this stage, which undergo folding while the blank is on this conveyor belt. The first folding is effected by a set of plough folders 55a (needed only for the bottom edge, as the top edge flap is not of double thickness) while the second folding to produce the spine form is effected by mechanisms contained in the housings generally indicated by reference 55b. For the proper formation of the spine along the bottom edge, an application of adhesive on the edge portion of the blank is necessary before folding and an adhesive applicator is indicated at 56.

As mentioned in connection with FIG. 1, the front blanks require no folding and no adhesive application at this stage, hence as will be observed there are no folding devices or adhesive applicators associated with the conveyor belt 54.

Both the belts 53, 54 run continuously, but when the back blanks are delivered to the position 5, they are moved away at right angles to their previous direction of travel towards position 6, i.e. generally to the left as seen in FIG. 2, by an intermittently-moving conveyor. Conveniently this takes the form of a pair of belts or chains each lying below a slot in a smooth plate along which the blanks can slide, said chain or belt having pusher members protruding through the slot to engage the top edges of the blanks being conveyed, the top edges being at the rear of the blank in relation to its new direction of motion. This intermittently-moving conveyor, which although not visible in FIG. 2 is of a form well known in the art, will be referred to as the second conveyor.

As each back blank reaches the position 5, it passes under a downwardly-facing brush which presses lightly downwards on the blank as it stands very briefly at position 5. When the blank commences its travel with the second conveyor, this brush ensures that the blank remains in contact with the pusher members which propel it and, as the top edge of the blank (which is now at its rear relative to its new direction of travel) passes under said brush, the previously folded-over top edge portion is caused to unfold again. This operation is not hindered by the pusher members, which engage the blank near its side edges while the top edge portion which is folded over and now unfolded again does not extend over the whole width of the blank.

While each back blank is being propelled by the second conveyor its side edge portions (which are now along its sides relative to the direction of travel) pass adhesive applicators, one of which is visible at 57, which serve the same purpose in relation to the side edges as does the applicator 56 in relation to the bottom edge, i.e. of providing the adhesive necessary to secure the edge portion which is then folded over by mechanisms contained within housings 58a to form a double thickness to give required stiffness in the spine of the finished sleeve. The side edge portions are not further folded before the back blank reaches position 6, their folding being completed at a later stage.

It is preferred to perform the first folding operation on the side edge portion, just mentioned, while the second conveyor is stationary. Therefore the mechanisms within housings 58a comprise movable folding blades arranged to operate upon the edge portions of a stationary blank.

At the position 6, as stated in connection with FIG. 1, each back blank is momentarily stationary, and at this time a record, already enclosed in an inner bag, is deposited upon the back blank. At this time, the top and bottom edge portions of the blank have been formed (but the top edge portion has been unfolded again and the bottom edge portion will have partly unfolded due to its own resilience) while the side edge portions have merely received adhesive and undergone the first stage of folding, i.e. to form a double thickness in preparation for forming of the spine on each side edge; thus more of the edge portions obstruct deposit of the record.

After deposit of a record upon each back blank at the position 6, that blank resumes travel in the same direction as it was travelling immediately before arrival at the position 6, and as it does so the top edge portion is again folded over, by the operation of a pair of hook-like fingers which are moved up from below the path of the blank along an arcuate path to engage its top edge portion and restore it to the folded position. This prevents the record being left at the position 6 by sliding off the back blank as the latter is moved away from position 6 by the pusher members of the second conveyor, and for further security a horizontally-reciprocating member (not shown) holds down the top edge portion during an initial part of its travel away from position 6.

From the position 6, the back blank is moved by the second conveyor to position 7. Here each back blank as it arrives is engaged by a further, or third, conveyor whose working run starts at this position. This third conveyor may be described as comprising a series of pockets each adapted to receive one back blank. The leading and trailing edges of each pocket are formed by bar-like members extending at right angles to the direction of motion of the blanks and having overhanging flanges to engage and hold in correctly-folded positions the bottom and top edge portions of the blanks. The third conveyor moves continuously.

As the back blanks are advanced in the pockets of the third conveyor, they pass and are operated upon by folders for the side edge portions of the blanks, to form the spines thereon, one set of such folders being contained in the housing indicated at 58b in FIG. 2. Here it is convenient to note that the folders within housing 58b, are similar to those in housings 55b, as they have to perform the same operation in the side edge portions of the back blank as the mechanism in housings 55b have to perform on the top and bottom edge portions, the blanks in both instances being in continuous motion past the folding mechanisms.

While all the foregoing operations are being performed upon the back blanks, the front blanks delivered to position 9 by the conveyor belt 54 have been travelling above the back blanks on a further conveyor 59 and as each back blank leaves the position 7 a corresponding front blank travelling above it is delivered by the conveyor belt 59 into a housing 60 containing feed mechanism to bring said front blank obliquely downward to meet the back blank in register.

Once the side edge portions of the back blank have been appropriately folded, the back blank is ready to receive the front blank. As each front blank moves obliquely down inside hous-

ing 60, adhesive is applied to the undersurface of the front blank over areas adjacent to its bottom and side edges. This adhesive applicator is not visible in FIG. 2 but is similar to an offset printing mechanism.

This feed mechanism (not visible in FIG. 2) which propels the top blank obliquely downward within housing 60 may take various forms but we prefer to provide pairs of driving rollers between which each front blank in turn is gripped and positively fed along the desired oblique path so as to give positive control of the position of each front blank. Said rollers are circumferentially grooved and narrow, and so disposed as to grip the blank along lines where no adhesive has been applied. The position of each back blank is of course accurately defined as it is still contained within a pocket of the third conveyor. The feeding of the front blanks is accurately timed so that each front blank meets a back blank in accurate register.

After the two blanks have thus come together to form a complete sleeve, which is still travelling on the third conveyor, the finished sleeve, containing the record in its bag, is subjected to sufficient pressure to produce a good adhesive bond between the adhesively-coated areas of the front blank and the bottom and side flaps of the back blank. Conveniently, such pressure is applied by a series of spring pads holding a pair of belts against the upper surface of the sleeve passing thereunder, said belts travelling at the same speed as the third conveyor, said pads preferably having working surfaces of such form that pressure is not exerted on the whole of each sleeve, but only over the areas within which adhesive is to be found.

A final conveyor (not visible in FIG. 2) under housing 60, receives the finished sleeve as it feeds clear of the third conveyor, and this final conveyor is operated continuously at a higher speed than the speed at which the third conveyor moves, so that as each complete sleeve passes sufficiently on to the final conveyor to take its drive therefrom, the sleeve is accelerated and moved clear of the flanged bar constituting the rear or trailing edge of the pocket of the third conveyor in which the back blank has been travelling so that the trailing edge of the finished sleeve is clear of said flanged bar before the latter commences to incline downwardly, to avoid possible damage to this trailing edge of the sleeve.

From the final conveyor, the finished, record-containing sleeves are discharged into a check-weighting unit generally indicated at 61. This unit comprises a rotatable assembly 62 arranged to receive successive sleeves at angularly spaced radial positions. Each filled sleeve enters this assembly horizontally and the assembly rotates so that the sleeve is then moved through an arcuate path turning through 180°, and at that position is normally expelled by any convenient form of ejector, to the position 13. However, while each filled sleeve is in said assembly 62, it will be observed that it passes through a position in which it is held vertically and at this position each sleeve is allowed to rest on a form of weighing mechanism. If the weight of a filled sleeve is approximately correct then it is allowed to be discharged to the position 13 but if as it goes through the vertical position it is found too heavy or too light (i.e. it is indicated that the sleeve contains more than one record or has failed to receive a record) then the weighing mechanism operates to inhibit discharge of the sleeve from the rotatable assembly 62 when the sleeve is brought adjacent to the position 13, but the sleeve is retained within the assembly 62 until said sleeve is pointing downwardly and then the sleeve is released into a reject bin in the lower part of the unit 61.

From the position 13, the filled sleeves pass to an overwrapping apparatus generally indicated at 63, which will not be described in detail here as it is no part of the present invention.

From the apparatus 63, stacks of overwrapped filled sleeves such as the stack 18 are obtained.

In the above, reference has been made to the deposit of a record, enclosed in an inner bag, upon the back blank and now it will be explained how the record, so enclosed, is brought to the position at which it is deposited on the blank.

Firstly, the inner bags are fed into the machine at the position 30 (shown on both FIG. 1 and FIG. 2) and travel along a conveyor below the conveyor 59 and above the second conveyor to a position adjacent to and at a higher level than the position 6 at which the record, in its bag, is deposited on the back blank. As each bag reaches the left hand end of the conveyor which thus feeds it, the open end of the bag, which is directed away from the viewer as seen in FIG. 2, is held open sufficiently for a record to be fed into said bag and the bag, now containing a record, is allowed to fall slightly on to the buffer stack 29 (FIG. 1).

The records enter the machine on a conveyor 64, said records conveniently, as shown, being in stacks on pallets, each pallet comprising a base 65 and a central pillar 66. The conveyor 64 discharges the loaded record pallets on to a table 67 and from here an operator moves the record stacks, with their pallets, as required to the feed-in position 21 (FIG. 1). As seen in FIG. 2, two stacks of records may be placed at the position 21, side by side. In FIG. 2 one complete stack 68 is shown at the feed-in position and a nearly exhausted stack 69 is also shown just beyond it. As drawn in FIG. 2, the machine is taking records from the nearly exhausted stack 69, the records being removed from the top of the stack and fed generally towards the viewer. At the position 21, each of the stacks 68, 69, is placed on a supporting platform which, as records are taken from the stack, is progressively raised so that with decreasing height of the stack the uppermost record in the stack being used is maintained at the same level so that mechanism thereabove can remove it.

The records are pushed horizontally, with their extreme edge portions engaged in channels at two diametrically-opposed points towards an inspection assembly generally indicated by reference 70.

During the feed of the records from stack 69 (or stack 68) to the inspection assembly 70, the opportunity is taken to remove from the sequence of records any metal supporting discs which may have been placed between them in the stacks on the pallets. Conveniently this is done by having a magnetic or capacitative sensing device immediately above the path of the records and arranging that whenever the response of said device indicates the presence of a metal disc, the portion of the channel members in which the record edges are engaged immediately adjacent to the sensing device shall separate slightly to allow the metal disc to drop. A suitable hopper or bin (not shown) may be placed below this position to receive such discs.

Because of the removal of the metal discs, there are gaps in the sequence of records approaching the assembly 70. Therefore, the records are fed towards said assembly rather faster than is required by the speed at which they are handled in said assembly, and at the position 22 (FIG. 1) a small stack of records is collected, records being fed to the top of said stack and removed one at a time from its bottom. This small stack then functions as a buffer store.

At a variety of positions in the machine described it is of advantage to provide means for checking that the records and blanks are correctly matched. The blanks may be provided with coded markings, preferably on parts of their inner surfaces so that such markings are not visible on the finished sleeves. Similar coded markings may be applied to the records, but at present we prefer to rely upon markings on the record pallets. The markings may in each case be such that they can be sensed by photo-electric or electromagnetic detectors, and such detectors are preferably placed, for example, at the positions where blanks leave the hoppers 51, 52 and at the positions 20, 21 where loaded record pallets enter the machine. Electronic circuitry connected to such detectors is then arranged to give warning indications as required. Such circuitry needs, of course, some provision for storage of detector outputs to allow for time differences when it is required to compare signals obtained from two sensing operations which cannot take place simultaneously.

Various portions of the machine described above will now be explained in more detail; the figures of the drawings illustrating the individual portions of the machine, to which reference will be made, in some instances show parts visible in FIG. 2 but with different references, to assist in directing attention to the figures best illustrating particular features as the description of these features is read.

Firstly, the blank feeding mechanism associated with hoppers 1, 2 (FIG. 2) will be described, reference now being made to FIGS. 3 to 3C.

Referring first to FIG. 3, the feed device comprises two hoppers 701 and 702 arranged side by side on a base 703. In between the hoppers 701, 702 is a housing 704 containing the driving belts for the mechanisms in each hopper which remove cardboard blanks therefrom, as will be described in detail later. The feed device illustrated is preferably used for feeding two blanks at a time, i.e. one from each of the hoppers 701, 702, to a machine for making record sleeves; the sleeves being made from a front blank and a back blank which are combined to form a finished sleeve. The back blanks are stacked, on edge, in the hopper 701 and the front blanks are stacked, on edge, in the hopper 702, the front blanks being fed one at a time in an upward direction towards a horizontal conveyor 705, and the back blanks being fed one at a time in unison with the front blanks, towards a horizontal conveyor 706 arranged at a lower level than the conveyor 705.

Referring now to FIGS. 3A, 3B and 3C the hoppers 701 and 702 each comprise, respectively, two side walls 707, 708 and 707a, 708a, a rear wall 709, 709a, a bottom wall 710, 710a and a top wall 711 which extends across both hoppers, the bottom walls being attached to the base 703.

A stack 712 of back blanks is supported in the hopper 1 on a pair of base plates 713, only one being visible in FIG. 3B, which are supported, at their ends, on rods 714 which extend between, and are fixed at their ends to, the side walls 707, 708. The sides of the stack 712 are controlled by side plates 715, only one being visible in FIG. 3B. A stack 716 of front blanks is supported in the hopper 702, in a similar manner to the stack 712 in hopper 701, on base plates 717 and rods 718 carried between and by the side walls 707a, 708a.

The hoppers 701, 702, and therefore the base plates 713, 717, are mounted on the base 703 so that both stacks of blanks are supported in a plane slightly off the vertical, as can be seen in FIGS. 3B, 3C. The upper part of the stack 712 is supported by two blocks 719 which engage the blanks near the top corners thereof, as shown in FIG. 3A. The surfaces of the blocks 719 which engage the blanks are angled, as shown at 720 in FIG. 3B. A small lug 721 is provided at the right hand end, as viewed in FIG. 3B, of the plates 713 to support the bottom corner of the stack 712.

The upper part of the stack 716 is supported by two freely rotatable rollers 722 which engage the leading blank at the positions shown in FIG. 3A. Two projections 722a are also provided against which lies the top corners of the leading blank. The bottom of the leading blank in stack 716 rests against two blocks 723 which are mounted on the right hand end, as viewed in FIG. 3C, of the plates 717. The faces of blocks 723 which engage the blanks are angled, as shown at 724 in FIG. 3C.

A sucker 725 (FIGS. 3A and 3B), provided with a single suction pad 725a, is provided to engage the leading blank, near the bottom edge thereof, in the stack 712 and present it, in a manner to be described later, to driven rollers 726, which co-operate with resiliently mounted rollers 727, 728, to feed the blank towards the horizontal conveyor 706. The rollers 726 are fixed to a shaft 729 carried between the side walls 707, 708. The rollers 727, 728 are mounted for free rotation in one end of arms 730, 731 respectively, which are fixed to axially aligned shafts 732, 733 (FIG. 3A). The shafts 732, 733 are each journaled in a bracket 734, fixed to the bottom wall 710. The rollers 727, 728 are urged towards the driven rollers 726 by springs, one of which is shown at 735 in FIG. 3B. A further lever 736 secured to shaft 733 carries an adjustable

stop 736a (FIG. 3B) so that the gap between the roller 728 and its co-operating driven roller 726 may be set to any required distance, for example, a distance slightly less than the thickness of a single blank. Also fixed, at one end, to the shaft 733 is a lever 737, the other end 738 being arranged to operate a micro-switch 739 in the event of two blanks being fed at a time by the sucker 725 which would cause rollers 727, 728 to move away from rollers 726.

A similar arrangement to that just described in the previous paragraph is provided in the hopper 2 and is shown in FIGS. 3A, 3C. The apparatus is in most respects the same, except for the sucker 725 which, as shown in FIG. 3A consists of a pair of suction pads 725a positioned side by side. The same references have been used in FIGS. 3A, 3C for parts which are the same, and serve the same purpose as those described with reference to FIGS. 3A, 3B. These parts will not be described again, but it is pointed out that in the case of the front blanks in hopper 702, the apparatus is arranged to feed the leading blank of the stack 716 in an upward direction towards the horizontal conveyor 705.

To assist the forward movement of the stacks 712, 716 towards their respective suckers 725, a joggling device is provided in each of the hoppers 701, 702 which consists of a pair of strips 741, positioned between the base plates 713 in the hopper 701 and between the base plates 717 in the hopper 702, only one of the strips 741 being visible in each of FIGS. 3B, 3C. The strips 741 are mounted on bearers 742 which are carried on eccentrically mounted shafts 743, which during operation of the device are constantly rotated in the direction indicated by arrows; as the shafts 743 rotate they give the strips 741 a movement through a circle having a radius equal to the throw of the eccentric. Thus the blanks are continuously joggled up and down and urged forwards towards the suckers 725.

The mechanisms for achieving movement of the suckers 725 to effect feeding of the blanks from the stacks 712, 716 are separate from each other but are substantially the same in design and operation. The main difference is that each of these two mechanisms is inverted with respect to the other so that back blanks are fed away from the stack 712 in a downward direction and the front blanks are fed away from the stack 716 in an upward direction. In the following description the mechanism for moving the sucker 725 in hopper 701 will be described in detail, and, to save duplication, where different references are applicable to corresponding parts in hopper 702 they will be written in brackets immediately following the references applicable to parts in hopper 701.

The sucker 725 is carried by a block 744 (744a) which in turn is carried by a tube 745 (745a), the block having internal drillings providing communication between the pads 725a and tube 745 so that suction may be applied to the pads 725a via a pipe 746 (746a) which connects the tube 745 (745a) through a rotary valve 747 (747a) mounted on a shaft 748 (748a), to a source of suction (not shown). The tube 745 (745a) is fixed in a frame 749 which is carried by two pairs of levers 750, 751 (750a, 751a), one lever of each pair being positioned on each side of the frame 749 (749a). In FIGS. 3B, 3C only one lever of each pair is visible and in FIG. 3A the levers 750 (750a) are not visible as they are directly behind the levers 751 (751a). Pivoted connections 752 (752a) between the frame 749 (749a) and one end of each of the levers 750 (750a), the other ends of said levers being slotted at 753 (753a). A pin 754 fixed between and carried by two side plates 755 (755a) mounted on rear wall 709 (709a), passes through the slots 753 (753a). The levers 750 (750a) also carry, between them, a roller 756 (756a) which runs on a cam 757 fixed to the shaft 748 (748a) which is rotatably mounted in the side walls 707, 708 (707a, 708a). A spring 758, (758a) is provided to keep the roller 756 (756a) in contact with the cam 757 (757a).

The levers 751 (751a) also have, at one end, a pivotal connection 759 (759a) to the frame 749 (749a), and are carried by a spindle 760 (760a) which extends between the side plates 755 (755a). The other end of the levers 751 (751a) carry a

roller 761 (761a) which runs on a cam 762 (762a) fixed to a shaft 763 (763a) which is rotatably mounted in the side walls 707, 708, (707a, 708a). A spring 764 (764a) is provided to keep the roller 752 in contact with the cam 762 (762a).

Referring now only to the mechanism contained in hopper 701, the shaft 748 has fixed to it a further cam 764, on which runs a roller 765 mounted on one end of a bell-crank lever 766 fixed to a pin 767 rotatably mounted in a bracket 768, the other end of the lever 766 carrying a spring 769 to keep the roller 765 in contact with the cam 764. An arm 770 fixed at one end to the pivot pin 767 carries, at its other end, a roller 771 which is arranged to engage the face of the leading blank in the stack 712 and relieve the weight of that stack from the lug 721 at certain times, as will be explained later.

To remove the leading back blank from the stack 712 the shafts 748, 763 are driven continuously, as will be described later, so that under control of the cams 757, 762 and 764 the following sequence of operations takes place.

The roller 771 is swung to the left, as viewed in FIG. 3B, about the pivot pin 767 to contact the leading blank of the stack 712 and move the bottom part of the latter slightly away from the lug 721 so as to relieve the weight of the stack therefrom. At the same time the sucker 725 is swung towards the left, as viewed in FIG. 3B, about the spindle 760, to engage and suctionally hold the leading blank in the stack 712, the suction being applied to the pad 725a at the proper time under the control of the rotary valve 747. The sucker 725 then starts to swing away from the stack so as to pull the bottom part of the leading blank away from the next succeeding blank, and past the lug 721. Whilst this is taking place the roller 771 remains in the same position and the blank is caused to bend about the roller 771 to help ensure that only one blank is picked up by the suction pads 725a. This bending of the blank round roller 771 causes those edges of the blank which contact the angled faces 720 of the blocks 719 to be pulled clear of the nip between the stack and the blocks 719. The faces 720 are angled so that once the blanks are free of the nip mentioned above, a blank is only being held by the sucker 725 and is in contact with the roller 771. When the bottom edge of the blank has passed the lug 721 the roller 771 is moved to the right, as viewed in FIG. 3B, so that the lug 721 again takes the weight of the stack 712; also at this time, the sucker 725 is moved in a downward direction.

The sucker 725 continues to feed the blank downwardly until it is gripped between the rollers 726, 727, when the suction is cut off and the sucker is then moved upwardly to the position shown in FIG. 3B. A blank is fed by the rollers 726, 727 along a curved guide plate 772 to be gripped between, and fed by, a pair of co-operating belts 773 which constitute the horizontal conveyor 706, towards further mechanism which does not form part of the present invention.

The leading blank of the stack 716 in hopper 702 is removed therefrom in the same manner as just described with reference to the stack 712 in hopper 701, except that the sucker 725 engages the leading blank near its top edge and feeds the blank upwardly, towards the rollers 726, 727, after pulling the top part thereof past projections 722a which serve the same purpose as the lug 721 in hopper 701. Also the rollers 722 in hopper 702 are not movable as are the rollers 771 in hopper 701, but they serve the same purpose in that the blank is bent round the rollers 722, which bending causes those edges of the blank which contact the angled faces 724 of the blocks 723 to be pulled clear of the nip between the stack and the blocks 723.

The rollers 726, 727 in hopper 702 grip and feed the blank upwardly and along a further guide plate 774 towards a conveyor 773 which constitutes part of the horizontal conveyor 705 and forms no part of the present invention.

Between the ends of the guide plates 772, 774, remote from the rollers 726, 727, and the horizontal conveyors 706, 705 respectively further pairs of rollers 775, 775a; 776, 776a respectively are provided, the rollers 775, 776 being driven and the rollers 775a, 776a being resiliently urged against

them. Adjacent each of the last mentioned pairs of rollers is a deflector 777, 777a respectively which are moved from the full-line position shown in FIGS. 3B, 3C to the chain-dot position by energisation of solenoids 778, 778a respectively. The

5 solenoids are both energised whenever either of the micro-switches 739 are tripped due to more than one blank being fed between rollers 726, 728 in either hopper 701 or 702. When the deflectors 777, 777a are in the chain-dot position of FIGS. 10 3B, 3C the blanks are guided into chutes which lead to hoppers 780, 780a (see FIG. 3) for collecting rejected blanks, the rejected blanks from hopper 701 passing through chute 779 and the rejected blanks from hopper 702 passing through chute 779a.

15 It is noted that if, at any time, it is desired to suspend feeding of blanks, this can readily be done by cutting off the suckers 25 from the suction source (not shown); it is not necessary to stop the movements of the various parts as no blank can be fed from either stack while the suckers are inoperative.

20 As stated before, a front blank and a back blank fed from hoppers 701 and 702 respectively are intended, at a later stage, to be joined together to form a sleeve for a record. It is therefore important that the two blanks fed together from the hoppers are a matching pair because the front blank usually 25 has at least a title printed on it and the back blank usually contains descriptive matter referring to the recorded material on the record. For this purpose both the blanks may have an identical code printed on them in such form that the codes may be sensed by detectors 781, 781a (which may for example be photo-electric or electro-magnetic devices) positioned 30 in the hoppers 701, 702. Such a detector is shown in each of the hoppers 701, 702 at 781, 781a respectively, the arrangement is such that if either detector senses a wrong code both solenoids 778, 778a are energised so as to cause rejection of 35 both blanks in the same manner as described above in relation to feeding two blanks at a time from one hopper.

The various shafts of the feed device are driven, through suitable gearing, from a driven unit shown diagrammatically in FIGS. 3B, 3C, at 782.

40 Next, the details of the mechanism for dropping a record (in its bag) on to each back blank will be described; illustration of this mechanism is provided by FIGS. 4 to 4F.

In FIG. 4 of the drawings a partly formed back blank 320 has been delivered to, and come to rest at, the position shown, 45 having been moved to that position, along a horizontal path in the direction of arrow A, by two fingers 104 carried on chain conveyors 105 which are driven intermittently from a drive unit (not shown).

50 The blank 320 is positioned, as described above, vertically below a stack BR of records, supported in a record feed device, generally indicated at 321. Records are fed, one at a time, to the top of the stack BR, from mechanism (not shown) which inserts the records into a bag, said mechanism being positioned above the device 321.

55 The device 321 comprises a base plate 322 and three side walls 323, the base plate 322 having a window 324 through which the records contained in the stack BR pass, as successive records are released from the bottom of the stack, as will be described later.

60 The stack is supported within the device 321, by three escapement mechanisms 325, 326, 327, carried by the base plate 322, and arranged so that one escapement mechanism is positioned adjacent each of three sides of the window 324, as shown in FIG. 4A. The bag in which each record is contained is open along one side, to allow for insertion of the record, and no escapement mechanism is provided at the side of the window 324 adjoining the open side of the bag, as such mechanism would be likely to foul the bag during the separation 65 of the bottom record from the rest of the stack, as will become clear later. If the apparatus were required to handle records only (i.e. the records were not contained in bags) the escapement mechanisms could be equispaced around the periphery of the record. As the mechanisms 325, 326, 327 are identical, only the mechanism 325 will be described in detail.

The mechanism 325 consists of a lower support plate 328, provided with a single finger 329 mounted thereon, and an upper support plate 330, provided with two fingers 331 mounted thereon (FIG. 4A). The plates 328, 330 are formed, respectively, on one end of rods 332, 333, which are slidably carried in bearings 334, 335, the latter being fixed, one above the other, in a lug 336 which extends downwardly from the underside of the base plate 322. The other ends of the rods 332, 333 are formed as domes and engage the surface of cams 337, 338 respectively, which are fixed to a shaft 339 journalled in the base plate 322, the rods 332, 333 being kept in engagement with their respective cams by means of springs 340 (FIG. 4C) mounted between the lug 336 and collars 341 fixed to the rods. To prevent the rods 332, 333 from rotating in the bearings 334, 335, pins 342, fixed in the bearings, extend into longitudinal slots (not shown) formed in the rods.

The shaft 339 and corresponding shafts 343, 344 of the mechanisms 326, 327 respectively all extend upwardly through the base plate 322, their upper ends being journalled in similar housings 345 carried on the upper surface of the base plate 322. A further shaft 346, journalled at one end in a housing 347 also carried on the upper surface of base plate 322, extends downwardly through the base plate and at its lower end carries a bevel gear 348 meshing with a further bevel gear 349 fixed to a drive shaft 350 which is driven one revolution at a time by a single-revolution clutch, generally shown at 351, to be described later, the driving member of which is continuously driven, in the direction shown by arrow B (FIG. 4B), by an input shaft 352, which in turn is driven from a drive unit shown diagrammatically at 152; shafts 350, 352 are axially aligned. The shafts 339, 343 are driven from the shaft 346 by toothed belts 353, 354 respectively. The shaft 344 is driven from shaft 343 by a further toothed belt 355.

The single-revolution clutch 351 is shown in FIG. 4B and consists of a driving member 356 fixed to the input shaft 352 and a driven member 357, fixed to the drive shaft 350. The members 356, 357 are both in the form of discs, the member 357 being of substantially larger diameter than the member 356. Fixed to the face of the disc 357 nearest the driving member 356 is a block 358, and a pin 359 on which an arm 360 is pivotally mounted. The arm 360 is provided with a tail 360a and also a projection 361 which engages in a recess formed in the member 356, as will be described later. The arm 360 is urged in a clockwise direction about the pin 359 by a spring 362. Pivotally mounted, at one end, on a stub shaft 363 parallel to the shafts 350, 352 is a lever 364 formed, at its other end, into a hook 365. A further lever 366 also pivotally mounted, at one end, on the shaft 363 is provided at its other end with a spring loaded plunger 367. A link 368 is pivotally attached, near one end, to the lever 366. The end of the link 368 nearest the pivot, carries a spring 369 which urges the lever 366 in an anti-clockwise direction about the shaft 363, the lever 364 being moved, in unison with the lever 366, by means of a flat spring 370, fixed to the lever 366. The other end of the link 368 is attached to one end of a short arm 371, the other end of which is fixed to the output shaft of a rotary solenoid 372.

Carried on the upper surface of the base plate 322 are a light source 373 and photo-cell 374, which are positioned so that the light beam therebetween is interrupted by the stack BR: the photo-cell 374 produces a signal upon any such interruption which is employed to stop feed of bagged records to the stack BR, such feed being resumed once the interruption ceases. The height of stack BR is therefore stabilised and the weight applied to the fingers 329, 331 does not become so great as to impede operation of said fingers. A further light source 375, and photo-cell 376 are positioned so as to detect the presence of a partly formed back blank approaching the rest position (i.e. the position of blank 320 in FIG. 4) beneath the device 321. The source 375 and photo-cell 376 are so arranged that a signal from cell 376, caused by a blank passing between the source 375 and cell 376, energises the solenoid 372. This causes the clutch 351 to engage, and drive the shaft

350 through one complete revolution, and then disengage, which in turn causes each of the shafts 339, 343, 344 to rotate through one revolution, and then stop, and the bottom record of the stack BR will be released from the escapement mechanisms 325, 326, 327, as will be described later, and drop on to the blank positioned below.

In FIGS. 4 and 4A the blank 320 has been delivered to the position shown, and prior to reaching that position a signal, produced by photo-cell 376 due to the blank 320 passing between it and its associated light source 375, has been transmitted to the solenoid 372 via a delay device (not shown) of any suitable type, so that the delayed signal energises the solenoid as the blank 320 comes to rest. The resulting operation of the solenoid 372, causes levers 364, 366 to move from the chain-dot position to the full line position (FIG. 4B). This allows the lever 360 to be swung clockwise about the pin 359 by spring 362, so that projection 361 will engage in the recess formed in the driving member 356 as the latter continuously rotates, thus causing the driven member 357 and therefore the drive shaft 350 to rotate.

After the various parts of the clutch 351 have reached the position shown in full lines in FIG. 4B and rotation of driven member 357 has started, the solenoid 372 is de-energised upon termination of the delay signal from photo-cell 376, and the spring 369 moves the lever 366 back to its original position (as shown in chain-dot lines), the lever 364 being moved by the flat spring 370 in the same direction as far as possible i.e. until the hook 365 engages the edge of member 357. By this time the arm 360 is moving round with driven member 357 and after the shaft 350 has rotated one revolution the tail 360a will come into contact with the spring loaded plunger 367, which is now in the position shown in chain-dot lines in FIG. 4B, and cause the lever 360 to swing anti-clockwise about pin 359 to disengage the projection 361 from the recess in the driving member 356 and stop the disc 357 as the block 358 prevents the lever 360 from further movement about pin 359. At the same time the hook 365 drops into a recess, also as shown in chain-dot lines in FIG. 4B, formed in the disc 357, to prevent any tendency of the disc to rotate in the wrong direction.

Due to the single revolution of shaft 350, produced as just described, whilst the blank 320 is stationary the mechanisms 325, 326, 327 operate to drop a record on to the blank in the following manner. As rotation of shaft 350 starts the bottom record of the stack BR has been separated therefrom, and is supported on the fingers 329, the stack being supported on the fingers 331 (FIG. 4). Rotation of shaft 350 causes the cams 337, 338 to be rotated by the shafts 339, 343, 344, and the fingers 329 are retracted (FIG. 4C) from beneath the record which drops downwards on to the blank 320. The fingers 329 then advance again (FIG. 4D) and the fingers 331 are retracted so that the stack BR drops slightly on to the fingers 329, which now support it (FIG. 4E). The fingers 331 are now advanced so that they separate the bottom record from the rest of the stack (FIG. 4F) and the stack is again supported on fingers 331, completing a cycle of operations of the mechanisms 325, 326, 327 so that they are left in their original condition, ready for the next operation which of cause occurs when arrival of a further blank is detected by photo-cell 376. This last operation of advancing fingers 331 to support the stack is possible because the centre part of a record (i.e. that part having no playing groove in it) is thicker than the rest, so that, in fact, the edges of adjacent records in the stack BR will be separated. In FIGS. 4C-4F this separation is shown disproportionately large, as it would not be visible if drawn to scale.

After the record has dropped on to blank 320, the latter is carried away from the position shown in FIG. 4, by conveyors 105 in the direction of arrow A.

It is now convenient to refer to FIGS. 5-5D; in FIG. 5, it will be seen that the blank, here with the reference 100, is being pushed, in the direction of arrow C, by two fingers 104 carried by chain conveyors 105 driven by sprocket wheels 106 keyed to a shaft 107, which is driven intermittently from a motor and

gear box (not shown). The arrangement is such that during each cycle of the intermittent drive the fingers 104, and therefore the blank 100, are stationary for half a cycle and moving for half a cycle. The shaft 107 is journaled at its ends in mountings fixed to side frames 108, which are carried on opposite ends of a number of cross frames positioned at intervals along the frame 108. Two of these cross frames are shown at 109.

The blank 100 is supported along each of its side edges, i.e. the edges extending in the direction of movement of the blank, by fixed plates 110, which are carried, between the side frames 108, on brackets 111 fixed to some of the cross frames 109. As the blank continues to be pushed along by the fingers 104, the leading edge 101 thereof passes over two rectangular windows 112, one in each of the fixed plates 110. Adjacent each of the windows 112 and on the undersurface of the plates 110 there is bolted a pair of brackets 113 which between them carry a short spindle 114 rotatably mounted therein. Fixed at approximately midway along its length to the spindle 114, is a plate 115, one part of which forms a flap 116, the other part 117 having a block 118 mounted at the end thereof. The block 118 is urged, by a spring 119, into contact with a cam 120. The two cams 120 are fixed to a shaft 121 rotatably mounted in supports 122 fixed to the cross frame 109, and driven from the shaft 107 by sprocket wheels 123 and chain 124. The arrangement is such that the flaps 116 are moved by the cam 120 to protrude through the windows 112 so as to lift the leading edge 101 of the blank off the top surface of the plates 110, as shown in FIG. 5.

The purpose of lifting the leading edge of the blank is to prevent it from hitting the leading carrier 125 of a pair of carriers 125, 126 which together form a pocket adapted to receive and grip the blank 100 and convey it continuously.

The carriers 125, 126 are mounted at their ends on chain conveyors 127, and extend at right angles to the direction of motion of the blank, between the fixed plates 110. The chain conveyors 127 are carried by a pair of sprocket wheels 128 which are mounted on the shaft 107 so as to be freely rotatable thereon, and are driven by a further pair of sprocket wheels (not shown). The chain conveyors 105, when they are actually moving are driven at a speed which is twice the speed at which the chain conveyors 127 are driven, i.e. the mean speed of the conveyors 105 equals that of the conveyors 127. It will thus be seen that the leading edge 101 of the blank would hit the carrier 125 if the flaps 116 were not provided.

The fingers 104 continue pushing the blank, the leading part of which is sliding over the top of the carrier 125, until the front faces (the faces in contact with the blank 100) of the fingers reach a position vertically above the centre of shaft 107, at which time the conveyors 105 and thus the fingers 104 are stopped, a brush 129 being provided (see FIG. 5) to ensure that the blank also stops at this position. The blank 100 is now in the position shown in FIG. 5A. The chain conveyors 127 are, however, still being driven, so the carrier 125 will now start to catch up with the leading edge of the blank. The carrier 125 is moved at a speed such that when it passes the leading edge 101 of the blank, the latter drops on to a ledge 130 (see FIG. 5E) provided on the carrier, with the spine 101a slightly spaced from a surface 131 which forms a right angle with the ledge 130.

The carrier 126 (see FIGS. 5C and 5D) consists of a beam 132, which extends between and is carried at its ends by the chain conveyors 127. The beam 132 is provided with end portions 133, bent up at right angles, each of which carries a rod 134. Midway along its length the beam 132 has a recess 136 cut in it through which passes one end 137 of a lever 137a pivoted at 138 to lugs 139 carried on the underside of the beam 132.

The end 137 of the lever 137a protrudes into a slot 140 formed in a bar 141 which is slidably mounted on the rods 134. The other end 142 of the lever 137a carries a roller 143 which is arranged to contact a stationary cam surface 144 as the carrier 126 reaches the position shown in FIG. 5A, the

roller being urged against the cam surface 144 by means of springs 145 carried on the rods 134 between the end portions 133 and the bar 141. A plate 147 (see FIG. 5D) is fixed to the top of the bar 141, and is so dimensioned that it extends beyond a face 146 of the bar 141 to form a lip 148, the purpose of which will be explained later.

The arrangement is such that the distance between the surface 131 of the carrier 125, and the face 146 of the bar 141 is equal to the length of the blank, i.e. the distance between the spines 101a, 102a. However, as the carrier is moved beyond the position shown in FIG. 5A, the bar 141 is moved a short distance rearwardly relative to the direction of motion of the carrier 126, by reason of the lever 137a being swung about its pivot 138 by the cam 144. On continued movement of the carrier 126 the face 146 of the bar 141 engages the blank 100 and in conjunction with the lip 148 holds the spine 102a in its proper folded position. At the same time the bar 141 starts to move the blank 100 in the direction of arrow C (FIG. 5). At this moment the leading end 101 of the blank is resting on the ledge 130 of the carrier 125, but, as mentioned before, slightly away from the surface 131. With further movement of the carrier 126, the bar 141 is returned to its original position by the springs 145 under the control of the cam 144, so that by the time the roller 143 runs off the cam 144 the blank has been pushed forwards by the bar 141 relative to the carrier 125 so that the blank is resiliently gripped between the surface 131 of the carrier 125 and the face 146 of the carrier 126. The blank 100 is shown gripped, as explained above, in FIG. 5B.

Next, the arrangement of the check-weighing unit 61 (FIG. 2) will be described in more detail, reference now being directed to FIGS. 6-6C. In FIG. 6, completed sleeves (each containing a record) being fed, in the direction of arrow D (FIG. 6), by pushers, one of which is shown at 126, carried on chain conveyors 127, driven by sprocket wheels 150 fixed to a shaft 151 driven, through suitable gearing, from a drive unit diagrammatically shown at 152. A short distance before the pusher 126 reaches a position above the centre of shaft 151, a pair of further pushers 250, only one of which is visible in FIG. 6, carried on chain conveyors 251, engage the trailing edge of the sleeve (considered in its direction of movement) and accelerate the sleeve, in the direction of arrow D, away from the pusher 126. The chain conveyors 251 extend between two pairs of sprocket wheels 252, 253, the sprockets 252 being fixed to shaft 254 which is also driven, through suitable gearing, from the drive unit 152, and the sprockets 253 being freely rotatable on a shaft 255. The shafts 151, 254 are driven from the unit 152 so that the linear speed of the pushers 250 is higher than the linear speed of the pushers 126.

In FIG. 6, a completed sleeve CS (containing a record) is shown being pushed by the pushers 250, over a horizontal support plate 256, towards a turnover and check-weigh unit generally indicated at 257. The unit 257 consists of a 12-station rotary indexing carrier wheel 258 made up of a back plate 259, in the form of an annulus, and a plurality of prongs 260 which are fixed to and extend at right angles from one face of the back plate 259. The wheel 258 is mounted vertically with its axis of rotation parallel to the direction of movement of, but offset to one side of, the chain conveyors 251 (as shown in FIG. 6A), so that the prongs 260 which are nearest to the conveyors 251 project towards oncoming sleeves on said conveyors. Each of the 12 indexing stations on the back plate 259 is provided with two pairs of prongs 260, arranged in radial alignment, but spaced apart from each other, and the prongs of each pair are separated by a distance slightly greater than the thickness of a completed sleeve, so as to form pockets 261 in which a sleeve can be loosely held as the wheel 258 is indexed in a clockwise direction, as viewed in FIG. 6A, as will be described later.

The sleeve CS is pushed by the pushers 250 into the pocket 261 positioned opposite the conveyors 251, until the pushers 250 are tipped backwards, in relation to their direction of movement, by reason of a tail 250a, provided on each pusher 250, running off the end of a fixed rail 262.

The wheel 258 is secured to a housing 263 which is fixed to a large gear wheel 264 mounted for free rotation on a shaft 265 rotatably carried in a further housing 266 fixed at one end to a support plate 267. A stub shaft 268, also fixed on the support plate 267, supports a rotatable collar 269 which carries, at one end, a gear wheel 270 which meshes with the large gear 264, and at the other end, a plate 271 (FIG. 6B) having six radial slots, the plate forming the driven part of a geneva indexing unit. A further stub shaft 272, journaled on the support plate 267, is driven continuously through a belt and suitable gearing, indicated diagrammatically as a dotted line, from the drive unit 152. On one end of the shaft 272 is fixed an arm 273 which carries a roller 274 at its outer end and forms the driving part of the geneva indexing unit. The arrangement is such that for each revolution of the stub shaft 272, the wheel 258 is rotated through 30° during one third of the revolution, and is stationary for the other two thirds.

When the pushers 250 tip back, as described above, and the sleeve is positioned in a pocket 261, the wheel 258 is indexed and a following sleeve from conveyor 251 may be fed into the next pocket 261. When three indexing movements have occurred after a sleeve has entered one of the pockets, that pocket comes to rest with the sleeve CS in a vertical position, as indicated by the reference 255a in FIG. 6A. Whilst the sleeve is being carried round by the wheel 258 it is supported on its inner edge, i.e. the edge facing the axis of rotation of the wheel 258, on two fixed surfaces 275. Each of these surfaces 275 has a step 276 (FIG. 6C) formed in it at such a position that as the sleeve reaches the position 255a it runs off the step 276 and drops on to a platform 277 forming part of a weighing device, generally indicated at 278. The device 278 consists of a frame 279 mounted on a base plate 280, in the form of a hollow box, which is carried on a fixed plate 281 which in turn is fixed to the other end (i.e. the end remote from the support plate 267) of the housing 266. The frame 279 carries a pivot pin 282 on which a lever 283 is freely mounted. The lever 283 is urged in an anti-clockwise direction (as viewed in FIG. 6C) by a spring 284 against an adjustable stop 285. Also freely mounted on the pivot pin 282 is a further lever 286, one end of which carries the platform 277; said platform 277 is placed at right-angles to the lever 286 and to one side of its centre-line, so that the weight of a sleeve applied to platform 277 causes pivotal movement of lever 286 on pin 282. The other end of lever 286 carries a thin plate 287 which is perforated at 288, the plate 287 being positioned so that it can swing, about the pivot 282, between a light source and a pair of photo-electric cells together constituting a detector device 289. The lever 286 is urged, in an anti-clockwise direction about the pivot 282 by a spring 290 mounted between the levers 283, 286.

The arrangement is such that when the sleeve CS drops on to the platform 277, as described above, the lever 286 and plate 287 swing, in a clockwise direction about the pivot pin 282, and come to rest at a position determined by the weight of the sleeve with its contents. The perforations 288 are arranged on the plate 287 in such a manner that, according to the position of the lever 286 and plate 287 when they come to rest, the photo-electric cells are illuminated and produce a signal to indicate one of three possible conditions of weight of the sleeve CS. These conditions are "light," "correct weight," and "heavy" which are indicated by, respectively, one, two, or no photo-electric cells being illuminated and correspond to sleeve CS containing respectively none, one, or more than one, record.

The characteristics of springs 284, 290 are so chosen that when the sleeve is of "correct weight," the lever 286 comes to rest just as it engages the lever 283, without substantial displacement of the latter. If the sleeve is "light" there will be much less movement of the lever 286 than with a sleeve of "correct weight," while if the sleeve is "heavy" then the lever 286 will move substantially beyond the point at which lever 283 is engaged, in spite of the need to tension spring 290 as well as spring 284.

If the sleeve CS contains only one record, a "correct weight" signal is produced by the detector device 289, and after the wheel 258 has been indexed three more times the sleeve CS is again horizontal (i.e. 180° from the position at which it was pushed into a pocket 261). Whilst the wheel 258 is in this position the sleeve 255 is ejected from the pocket 261 by a reciprocating pusher 291, in a direction transverse to the longitudinal axes of the prongs 260, and indicated by the arrow E in FIG. 6A, until the leading edge of the sleeve (considered in the direction of arrow E) is gripped between a driven belt conveyor 292 and a pressure roller 293, which cooperate to feed the sleeve CS towards devices (not shown) for enclosing the sleeve in an outer wrapper.

15 The pusher 291 is carried by a pair of rods 294 (only one being visible in the drawings) which are each mounted for reciprocation in a pair of blocks 295 (only one pair being visible in the drawings) fixed to the base plate 280. A lever 296 is connected, at one end, to the pusher 291 and at the other end to a further lever 297 which is fixed to the right hand end (as viewed in FIG. 6) of the shaft 265. The other end of the shaft 265 has an arm 298 fixed to it, the arm connecting with a link 299 which in turn is connected to an operating lever 300, near one end thereof. The operating lever 300 is pivotally mounted 20 on the support plate 267 at 301. The end of the operating lever 300 remote from the link 299 carries a roller 302 which engages a cam 303, fixed to the further stub shaft 272, a spring 304 keeping the roller in contact therewith. As the cam is continuously rotated the pusher 291 reciprocates in such timed 25 relation to the carrier wheel 258 that the pusher 291 is operated whilst the carrier wheel 258 is stationary.

A hooked lever 305, pivotally carried on the support plate 267, is connected, by links 306 to the output shaft of a rotary solenoid 307. A further hooked lever 308 is fixed to the 30 operating lever 300.

The arrangement is such that the solenoid 307 is energised on receipt of a "correct weight" signal from the detector device 289 which causes the hooked lever 305 to assume the position shown in FIG. 6B in which case the roller 302 remains 40 in contact with the cam 303. The electrical circuitry of the apparatus is arranged so that once the solenoid has been energised, it remains in that condition until de-energised by either a "light" or "heavy" signal from the detector device 289, caused by the sleeve CS containing either no, or more than one, record, respectively. It is arranged that when the solenoid 307 is de-energised, as explained above, the roller 302 is engaging the highest part of cam 303, so that the further hooked lever 308 is in a position such that the hooked lever 305 may be brought into interlocking engagement with the hook on lever 308 by a spring 309. This prevents the roller 302 from following the cam 303 during its next revolution, so that the sleeve having either no, or more than one, record in it is not ejected from the pocket 261 by the pusher 291. It is pointed out that as the wheel 258 is indexed through three stations 55 between the weighing device 278 and the pusher 291, the signal produced by the detector device 289 is stored, this being done by any convenient known means (conveniently a three-stage shift register) during this period.

60 Sleeves which are not ejected by the pusher 291 are carried round by the wheel 258 a further three stations, during which time they are held in the pockets 261 by a guide 310, until they are again vertical (i.e. 180° away from the position 255a). As the wheel comes to rest at this station the sleeve runs off 65 the end of guide 310 and drops vertically downwards against a wall 311 on to a conveyor 312 which forms a reject hopper from which sleeves may be collected as necessary.

The mechanism for inserting the records into bags is shown in FIGS. 7-7E. Referring to these figures, in this mechanism a paper bag 160 is fed, in the direction of arrow F (FIG. 7B), by a finger 161, mounted on a chain conveyor 162 carried by a sprocket wheel 162a fixed to and continuously driven by shaft 162b, towards a record insertion device 163. At the same time a record 164 is fed, in the direction of arrow G (FIG. 7B), 70 towards the device 163 by a pusher 165 mounted on a further

chain conveyor 166 carried by a sprocket wheel 166a fixed to and driven continuously by shaft 166b. The shafts 162b, 166b are both driven by suitable gearing (not shown) from an input shaft 208 (FIG. 7) which in turn is driven from a continuous drive unit diagrammatically shown at 209. The conveyors 162, 166 are arranged so that the bag and the record are moved towards the device 163 in the same plane, but at right angles to one another, as shown in FIG. 7B. The bag 160 is oriented so that its open edge is parallel to its direction of movement and is facing in a direction towards the record, so that the latter may be inserted into the bag as will be explained later.

The device 163 consists of a box-like structure, open at the top and bottom, and having a front wall 167, a rear wall 168 and two side walls 169, 170. The side wall 169 is shaped to receive and support the right hand end (as viewed in FIG. 7) of a housing 171 along the top surface of which the bag 160 is fed by the finger 161, and the front wall 167 is shaped to receive and support the right hand end (as viewed in FIG. 7A) of a pair of side frames 172 on which are mounted guides 173 which support and guide the record 164 as the latter is pushed by pusher 165.

The guides 173 are arranged parallel to each other and are spaced apart a distance such that the record 164 is supported at diametrically opposite points in vee-shaped grooves 174 (see FIG. 7) provided along the mutually facing surfaces of the guides 173. The pusher 165 is formed with two upwardly extending projections 165a which are also formed with vee-shaped grooves, as shown in FIG. 7A. The record is thus supported at four points round its periphery, which ensures that it does not tilt whilst being moved. The guides 173 extend in the direction of arrow G to a position level with the front wall 167.

The finger 161 feeds the bag 160 until the leading edge thereof is gripped between a driven roller 175 and a further roller 175a resiliently urged against the roller 175. The roller 175 is mounted on a shaft 176, supported in bearings mounted on the front and rear walls 167, 168 respectively. The rollers 175, 175a are positioned close to the front wall 167 (see FIG. 7B) so that they grip the bag adjacent the open edge thereof. At the same time as the rollers 175, 175a grip the open edge of the bag, the edge opposite that edge is suctionally gripped from above by suction applied to a suction box 178 along the underside of which runs a continuous perforated belt 179 carried between a pair of pulleys 180, 181. The pulley 180 is fixed to the shaft 176 and the pulley 181 is mounted on a further shaft 182 carried between the rear wall 168 and a partition 183 (FIG. 7B).

Mounted respectively on stub shafts 184, 185 are two suction wheels 186, 187, arranged vertically above one another, the wheel 186 being positioned above the plane along which the bag 160 is fed, and the wheel 187 being positioned below said plane (see FIG. 7). Suction from a source (not shown), is applied to the wheels 186, 187 through two chambers 188.

The wheels 186, 187 are eccentrically mounted on their respective shafts 184, 185 in symmetrical opposition so that during each revolution of the wheels their peripheries move, for the first half revolution, away from each other, and, for the second half revolution, towards each other. The roller 175, the perforated belt 179, and the wheels 186, 187 are all driven intermittently, through suitable gearing (not shown) from an input shaft 210 (FIG. 7) which in turn is driven intermittently by a drive unit diagrammatically shown at 211.

On continued movement in the direction of arrow F (FIG. 7B), of the bag, the leading edge thereof passes between the peripheries of the suction wheels 186, 187 which at this moment are almost touching (as shown in FIG. 7) so that suction will be applied to the two faces of the bag to hold the upper and lower faces thereof to the wheels 186, 187 respectively. As the bag is moved further, the two faces of the bag are pulled apart, due, as explained above, to the peripheries of the suction wheels 186, 187 moving away from each other, until, after half a revolution of the wheels 186, 187 the mouth of the bag is held open by an amount sufficient to permit entry of the record 164.

The record 164 is fed by pusher 165 to a position such that a further pusher 189, having a vee-shaped groove formed in its leading face and travelling at a higher speed than the pusher 165, engages the record and accelerates it away from the pusher 165. The pusher 189 is carried by two chain conveyors 190 and the leading face of the pusher 189 is arranged to engage the record between the projections 165a of the pusher 165 (FIG. 7). The chain conveyors 190 are carried by two pairs of sprockets 191, 192, the sprockets 191 being freely rotatable on a shaft 193 carried between brackets 194, and the sprockets 192 being fixed to a driven shaft 195 carried between two fixed walls 194a which extend between the walls 167, 168. The shaft 195 is driven through suitable gearing (not shown) from the continuously driven input shaft 208. The pusher 189 is pivotally mounted on the chains 190 and is urged in a clockwise direction (as seen in FIG. 7A) by a torsion spring mounted on its pivot, the pusher being kept in the correct orientation for engaging the record 164 by two rails 196, which extend to a position just beyond the suction wheels 186, 187 (considered in the direction of movement of the pusher 189).

FIG. 7C shows the record 164 being pushed by the pusher 189, and also the bag 160 which has just passed into contact with the suction wheels 186, 187, the closed edge of the bag being supported by the perforated belt 179.

In FIG. 7D the bag has been opened, as explained above, and the record is being pushed into the bag by the pusher 189. When the record is completely inside the bag i.e. the edge of the record is in contact with the sealed edge of the bag opposite the open edge, it also pushes the bag, which slides across the perforated belt 179 whilst still being supported by it. The pusher 189 continues pushing the record, and thus the bag, until the now leading edge of the bag (considered in its direction of movement which is now that shown by arrow H) touches a rubber pad 197 mounted on the rear wall 168, this position being illustrated in FIG. 7E. As the bag touches the pad 197 the pusher 189 runs off the rail 196 and pivots in a clockwise direction away from the record as shown in chain-dot line in FIG. 7E. Also at this moment the suction to the perforated belt is cut off and the bagged record is allowed to drop downwards as shown by the arrows J in FIG. 7E. The bagged record drops on to the upper face of a pair of support bars 198, 199 which are respectively fixed to pivot pins 200, 201 carried in brackets 202 fixed to the inside faces of the side walls 169, 170. The bars 198, 199 are arranged, to be moved to the position shown in chain-dot lines in FIG. 7, this movement being controlled by a pneumatic cylinder 204 the piston of which is fixed to one end of a lever 205, the other end of which is fixed to the pivot pin 201 of bar 199. A further lever 206 is fixed at one end to the pivot pin 200 of bar 198 and the two levers 205, 206 are connected by a link 207 so that the bars 198, 199 are moved in unison by the cylinder 204. When moved as just described the bagged record is allowed to drop further, in the direction of arrows J in FIG. 7E, on to the top of a stack of bagged records.

There remains to be described the details of the parts of the machine through which the records pass before they are inserted in bags as just described. Attention is next directed to FIGS. 8-8F, depicting the part of the machine through which records first pass.

Referring first to FIG. 8 two stacks of records 390, 390a are shown respectively positioned beneath suction feed assemblies 391, 391a arranged to remove successive records from the top of the stacks. The stack 390 is shown after removal of some records therefrom by assembly 391, and when the last record has been removed, the assembly 391a is operated to start removing records from the top of stack 390a. Whilst records are being removed from stack 390a, a further stack is positioned beneath assembly 391 which operates, after the stack 390a has been exhausted, and so on. Records removed from the stacks 390, 390a are placed, by the associated feed assembly, between a pair of horizontal guides 392, of which only one is visible in FIG. 8, along which the records are

pushed, in the direction of arrow K, by fingers 393 carried on chain conveyors 394. On reaching the right hand end of the guides 392 (as viewed in FIG. 8) the records drop on to the top of a small stack 395 (which functions as a buffer store) and are removed one at a time from the bottom of stack 395 by mechanism (not shown) which forms no part of the present invention. The stacks 390, 390a are carried on pallets 396 which are movable over a flat horizontal table 397 to the positions shown. Each pallet is provided with a vertical central pillar 398, which passes through the central holes of the records, and three holes arranged symmetrically around the centre thereof and within an area corresponding to the label area of the record (i.e. that part in the centre of the record having no playing groove formed in it). When a pallet is positioned below one of the feed assemblies 391, 391a the three holes therein are arranged to line up with three further holes provided in the table 397 so that three rods 399 (FIG. 8) may project through the aligned holes to lift the stack of records as will be described later, to a position adjacent the associated suction feed assembly.

As the mechanisms for removing records from the stacks 390, 390a are identical, in the following description only the mechanism for removing records from stack 390 will be described in detail.

Referring now to FIGS. 8A, 8B and 8C the rods 399 are secured at their lower ends (FIG. 8B) to a triangular platform 400 having a bearing 401 fixed to each of its corners. The bearings are slideable on guide bars 402 which extend vertically between the underside of the table 397 and a base 403. The platform is raised and lowered between the bars 402 by a chain 404 which passes round sprockets 405 carried on stub shafts 406, the lower one of which is driven from a reversible motor 407 by a further chain 408. Fixed to one of the guide bars 402, at a position near to the base 403, is a micro-switch 409, and at a position near the table 397, is a further micro-switch 410.

In operation a pallet 396, carrying a stack of records, is moved to the position shown in FIG. 8B, where it comes up against a stop 411. At this stage the platform 400 is stationary and at the lower end of its path of movement, so that the upper ends of the rods 399 are below the table 397. In this position the holes in the pallet 396 line up with the holes in the table 397. The arrangement is such that after the pallet engages the stop 411, a start button (not shown) is depressed to start the motor 407 which drives the chain 404 in a direction such as to start raising the platform. This causes the rods 399 to pass through the aligned holes in the table 397 and pallet 396 to engage with and raise the stack of records carried on the pallet. This movement continues until a micro-switch 412 is opened, which causes the motor 407 and thus the platform 400 to stop. The switch 412 is operated by one end 413 of a lever freely mounted on a pivot pin 414 which is supported as will be explained later. The other end of the lever is formed as a finger 415 which rests on top of the stack of records. As records are removed from the top of the stack the height thereof will be reduced and the finger 415 will thus swing anti-clockwise on the shaft 414 until the end 413 of the finger 415 closes micro-switch 412, which causes the motor 407 to again start driving the chain so as to raise the platform. The level of the top of the stack is thus kept at a reasonably constant height. As the stack moves upwards towards the finger 415 it is guided laterally by two pairs of posts 416, 416a (FIG. 8A), thus keeping the sides of the stack substantially vertical.

The suction assembly 391 is shown in detail in FIG. 8C and consists of a housing 417 which carries three suction pads 418 equispaced round a flange 419 provided at the bottom of the housing. The pads 418 are connected by pipes 424, carried in housing 417, to a suction pipe 425 which is in turn connected to a source of suction (not shown). A further pipe 426, also carried in the housing 417 is connected to a source of pressure air (not shown).

A bush 420 is provided with a flange 421 which is fixed to the underside of flange 419, and extends into a vertical bore

422 formed in the centre of the housing 417. The bush 420 is provided with a hole 427 which aligns with the pipe 426, and a longitudinal slot 428 formed in its inner surface between the hole 427 and the top end of the bush. Passing down the centre 5 of the bush 420 is a plunger 423 provided at its upper end with a flange which engages the top end of the bush 420 and prevents the plunger 423 from falling out of the bush 420. The plunger 423 has a circumferential recess 429 which, during separation of the top record from the stack, becomes aligned 10 with hole 427 in bush 420. The plunger extends below the suction pads 418 and is formed at its lower end into a short cylindrical nose 430, having a diameter which is less than the diameter of the central hole in a record, and a slot 431 formed in its end face. The recess 429 is in communication with the slot 431 by means of a hole 432.

The assembly 391 is mounted so that it may be moved vertically towards and away from the top of the stack 390 as it removes successive records therefrom. For this purpose there is provided a bar 433 (FIG. 8B) which extends vertically upwards from the top of the housing 417, through a fixed bearing block 434 in which the bar 433 can slide. The block 434 is carried between cross members 435 which are fixed at their ends to side frames 436 of the apparatus. The blocks 434 are so positioned that the assembly 391 moves in a vertical path which is slightly offset to the left (as viewed in FIG. 8B) of the vertical centre line of the stack 390. The assembly 391 is raised and lowered by a cam 437, fixed to a cam shaft 438 which rotates as shown by the arrow in FIG. 8B, on which runs 20 a roller 439 carried by an arm 440 pivoted at one end to a stub shaft 441 and at the other end to the top of the bar 433. The roller 439 is kept in contact with the cam 437 by a spring 442.

Before the top record of the stack can be separated therefrom, it has to be moved to the left (as viewed in FIG. 35 8B) so that its central hole is in vertical alignment with the nose 430 of the assembly 391. For this purpose, the finger 415, previously mentioned as a level detector for the stack 390, is moved by a cam 443, also fixed to the cam shaft 438, on which runs a roller 444 carried by one arm of a bell-crank 40 lever 445, pivoted at 446. The other arm of the lever 445 supports, and is freely connected to the pivot pin 414. To allow for the sideways movement of the top record of the stack, the two posts 416a (FIG. 8A) have their stack engaging faces shaped, near their top ends, as shown in FIG. 8B at 447. The 45 end of the finger 415 which engages the record is shaped as shown in FIGS. 8D-8F. The face 415a is of such depth that it engages the edge of only the top record, the face 415b engaging the top surface of the top record, and the face 415c is arranged to engage the edge of the top record, after the latter has been displaced and the finger withdrawn, so that the finger cannot move to displace the next record until the top record 50 has been lifted away. This situation is shown in FIG. 8E, where in chain dot lines a record which has not been picked up, is indicated.

The removal of a record from the top of stack 390 will now be described. With the parts positioned as shown in FIG. 8B, the switch 412 is open, and the motor 407 stopped. The finger 415 is resting on the top record. The finger moves forward (to the left in FIG. 8B) and pushes the record until it engages the shaped portion 447 of the posts 416a, at which position the central hole of the record is vertically below the nose 430. The assembly 391 is lowered and the nose 430 locates in the central hole of the top record and rests on the next lower record, the central hole of which is still on the vertical centre line of the stack 390 (FIG. 8D). The finger 415 is then moved back so that it disengages from the top record and rests on the next lowest one, ready to move it to the left. As the housing 417 is still moving downwards the plunger 423 will move upwards relative to the bush 420, to bring recess 429 in alignment with hole 427 in the bush 420, and the further pipe 426 in housing 417. This action lifts the flange, provided at the top of the plunger 423, clear of the top of bush 420, which puts the further pipe 426 into communication with the space between the top of the plunger 423 and the end of the hole 422 in the

housing 417, via hole 427 and slot 428. The housing 417 continues downwards, until the pads 418 engage the label area of the record surface, when suction is applied to the pads 418 and pressure air is applied through pipe 426. The pressure air feeds into recess 429, through hole 432 and out through slot 431 in the end of nose 430, to assist in separating the top record from the next lower one. Pressure air also feeds from hole 427 along slot 428 in bush 420, and into the space above the top of plunger 423. The pressure air acts on the top of plunger 423 and also on the closed end of hole 422 in housing 417. Due to the plunger being unable to move downwards, as the nose 430 is in contact with the stack 390, the housing 417, and thus the pads 418, are forced upwards, and the top record lifted, to separate it from the stack, by the suction applied to the pads. When the record has been separated, the pressure air in pipe 426 is turned off and plunger 423 returns to the position shown in FIG. 8C. The assembly 391 is lifted further, by cam 437, until the record is so positioned that it can be gripped by two gates 448, 448a (FIGS. 8A, 8B), at two diametrically opposite points, which are formed as movable parts of the guides 392 (FIG. 8E). The gates 448, 448a are fixed to one end of levers 449, 449a respectively, the lever 449 being freely carried on stub shaft 441, and the lever 449a being freely carried on a further stub shaft 450. The other ends of the levers 449, 449a are pivotally connected at 451. The lever 449 carries a roller 452 which runs on a cam 453 fixed to cam shaft 438. By the time the record being lifted on the pads 418 has reached the position shown in FIG. 8E, the gates 448, 448a have been moved out of alignment with the guides 392 as shown in that Figure. The assembly 391 is now stopped in its upward path, whilst the gates are moved towards the record, by cam 453 until they grip the record, at which point the suction is cut off from the pads 418 and the assembly 391 moves upward again to disengage the nose 430 from the central hole in the record. The record is then engaged by fingers 392 which push the record, in the direction of arrow K (FIG. 8) and deliver it to the top of the small stack 395.

Included in the stack of records 390 are a number of metal supporting discs (not shown) which are of the same dimensions as a record, but are not delivered to the stack 395. The metal discs are fed from the stack, as they reach the top thereof, in the same way as a record, but as they are being pushed along the guides 392, by finger 393, their presence is detected by a magnetic or capacitative sensing device 454 (FIG. 8A) which energises a solenoid 455 to cause a further pair of gates 456, in the guides 392 and similar to gates 448, 448a, to be moved out of alignment with the guides 392, so that the metal discs drop into a collection box 456a (FIG. 8).

The cam shaft 438 is driven from a further shaft 457 via a single-revolution clutch 458, which is operated upon energisation of a solenoid 459. The shaft 457 is driven from a drive shaft 460, by a chain 461, which is driven continuously from a drive unit diagrammatically shown in FIG. 8A at 462. The clutch 458 is constructed and operates in exactly the same manner as the clutch 351 and solenoid 372 shown in FIGS. 4A, 4B.

The arrangement is such that when the last record has been removed from the stack 390 the switch 410 is closed, by platform 400, which starts the motor 407 to cause the platform, and thus the rods 399, to descend until the platform closes switch 409 to stop the motor 407. The rods 399 are now retracted below the table 397 and the empty pallet 396 can be replaced by one carrying a further stack of records.

Closing of the switch 410, as mentioned above, also causes feed of records to be continued from stack 390a by the assembly 391a in the same manner as just described in relation to stack 390 and assembly 391.

When the last record of stack 390a has been fed by assembly 391a, records are again fed by assembly 391, the changeover taking place after a short time delay so that the last record from stack 390a can be pushed along the guides 392 to a position so that it does not impede the operation of assembly 391.

From the stack 395, records are taken one at a time to be inspected before being fed on (if satisfactory indications are found on inspection) to be inserted in bags as previously described. The mechanisms for presenting the records to the inspection devices will next be described, with references to FIGS. 9-9D. In this mechanism the records are carried round a path generally in the form of a slightly incomplete figure-eight. To effect this, the mechanism includes two rotatable heads 500, 501; the head 500 has four record-carrying members 502 and head 501 has four record-carrying members 503. The heads 500, 501 are fixed to shafts 504, 505 respectively which are driven intermittently in 90° steps from a drive unit diagrammatically shown in FIG. 9B at 506. The members 502 on the head 500 are disposed to support a record above each record-carrying member while the corresponding members 503 on the head 501 are each arranged to support a record below the record-carrying member. The purpose of this difference is to allow the upper surface of records to be inspected while they are carried by record-carrying members 502 of the head 500 and the lower surface of records to be inspected while they are carried by record-carrying members 503 of the head 501.

On the head 500, each record carrying member 502 comprises an upward facing disc 507 carried on a shaft 508, which is rotatably supported by and slideable in a bearing 509, and with a central projection 510 to engage through the central hole of a record placed thereon. Said central projection preferably is in the form of two hooked and spreadable catch members 511, which can be inserted through the centre hole of a record and then spread, as shown in FIG. 9D, to ensure retention of the record on the record-carrying member in a properly centred position.

The record-carrying members 503 of the head 501 have to support a record from above, so that its lower surface may be inspected, and each has three downwardly-facing suction pads 512, so disposed as to be symmetrical about the centre hole of a record supported thereby.

As each record-carrying member 502 of the head 500 comes below the position 22 (FIG. 1) a record is dropped on to it. As mentioned above, there is a small stack of records below position 22, and it is the lowest record of that stack that is dropped on to the member 502, the mechanism for thus dropping records being similar to that associated with the stack of bagged records, already described with reference to FIGS. 4-4F. Once the record is upon the member 502, the head 500 rotates 90° counter-clockwise (as viewed in FIG. 9) to present a further member 502 in position to receive the next following record.

During this 90° rotation of the head 500, a wheel 513, fixed to the shaft 508, engages and rolls along a stationary rail 514 thus causing shaft 508 and disc 507 to rotate on their own axis so that the record on disc 507 is revolving on completion of said 90° movement. With the head 500 in this position the revolving movement is maintained by engagement between the wheel 513 and a constantly rotating driving wheel 515. While the next following record is being received by the head 500, the first record delivered thereto is undergoing inspection and when, said next following record having been duly received upon its corresponding member 502, the head 500 makes a further 90° counter-clockwise rotation, the first-mentioned record is brought to another position at which it undergoes further inspection and then when yet another record has been placed on a third member 502, subsequent 90° rotation of the head 500 brings the first-mentioned record to a position at which the member 502 of head 500 which carries it is below a member 503 of head 501. At this stage, the first-mentioned record is transferred to the head 501, the member 503 of head 501 being lowered slightly to bring suction pads 512 of the member 503 of the head 501 into contact with the record, and suction being applied to those pads.

Said lowering is effected mechanically by a cam 516 which permits a corresponding lift of the member 503 before it leaves the position 25, the member 503 being carried by a tu-

bular spindle which is vertically slidable and biased upwardly by a spring 518 to maintain a follower 519 at its upper end against cam 516. An additional lift is given to the suction pads relative to the rest of the member 503, by mounting each suction pad on a small piston 520 movable in a cylinder 521 forming part of the member 503, suction being applied to the pad through said cylinder and a hollow piston rod via suction pipe 522 from a continuously operating pump 523; with this arrangement, once suction is applied and a record engages the pad, pressure drop in the cylinder 521 lifts the piston 520 and hence the pad relative to the cylinder and the rest of the member 503. The pumps 523 of all the members 503 are driven by a sun wheel 524 engaged with individual driven gears 525 on the several pumps.

Once this transfer is accomplished the head 501 rotates through 90° clockwise at the position the record is then brought to, its undersurface is inspected and when the head 501 makes a further 90° rotation, the record is brought to a position at which it is released, by terminating the supply of suction to the pads of the member 503, and drops slightly to a conveyor device 526 (FIG. 9, 9C) providing channels 527 for engaging the edges of the record clear of its playing surface, and pushers 527a to propel the record towards the position at which the inner bags are presented to receive records, adjacent to their position 6 (FIG. 2) at which the records in their bags are deposited on the back plates.

Suction is cut off from the pads of each member 703 at the appropriate position by venting the associated pipe 522 to atmosphere through a valve 528, which at this time is in alignment with operating plunger 529 of a solenoid 530 (FIG. 9C). The fall of the record on to conveyor device 526 is minimised by lowering the member 503, a further cam 531 engaging follower 519 for this purpose.

However, each record is only deposited on to the conveyor device 526 if during the inspection operations performed on it while it is being carried by the heads 500, 501 no fault justifying rejection of the record has been found. In the event such a fault is found, suction is maintained (i.e. plunger 529 is held up) on the pads of the member 503 of head 501 carrying that record when the latter is brought above the conveyor 526 and such suction is maintained until the head 501 has made a further 90° clockwise rotation. Suction is then released by a further solenoid (not shown) similar to the solenoid 530 and the record drops off the head 501 into a suitable bin or hopper (not shown) for faulty records.

It will have been noted in the discussion of heads 500 and 501 that while each record is on the head 500 it is brought to two positions at which it is inspected while when it is on the head 501 there is only one inspection position. Conveniently, at the first inspection position while the record is on head 500 inspection for warp and concentricity of the record is effected, and also the record is cleaned in preparation for inspection of its upper and lower surfaces, these inspections being effected with the record revolving.

At the second inspection position while the record is on head 500, the upper surface of the record is inspected as desired and similar inspection of the lower surface of the record is performed while the latter is at the single inspection position during its support by the head 501, these inspections being performed with the record stationary, but a suitable scanning of its surface being effected by the inspection devices.

It will be seen from the above description of a preferred embodiment that use of the invention provides an efficient packing machine for records or like articles. The invention is not however limited to the specific form of machine disclosed, a variety of modifications of structure being possible without departing from the scope of the invention.

We claim:

1. A packing machine for records or like articles, comprising first feed means for feeding a first series of sleeve blanks one at a time through an insertion zone to a uniting device, record feed means for depositing records one at a time in said

insertion zone, said record feed means being arranged to operate in synchronism with said first feed means so that each record is deposited in said insertion zone at a time when a blank of said first series is in said insertion zone so as to be received upon said blank, and means for delivering sleeve blanks of a second series one at a time to said uniting device in synchronism with the arrival of the blanks of the first series therat, said uniting device being arranged to secure each blank of the second series to the simultaneously-arrived blank of the first series so as to form a complete sleeve enclosing the record previously deposited on the blank of the first series.

5 2. A machine as claimed in claim 1, in which the first feed means comprises an intermittently-moving conveyor arranged so that each blank of the first series is stationary in the insertion zone while the record is deposited on said blank.

10 3. A machine as claimed in claim 2, in which the first feed means also comprises a continuously-running conveyor arranged to carry the blanks of the first series from the insertion zone to a uniting device.

15 4. A machine as claimed in claim 3 in which said continuously-running conveyor has a series of pockets each adapted to receive a blank of the first series with a record upon said blank.

20 5. A machine as claimed in claim 1, including record bagging means for inserting each record into a bag before deposit of the record upon a blank.

25 6. A machine as claimed in claim 5 in which the record bagging means comprises a bag feed arranged to take bags singly from a hopper and convey each bag in succession to a position adjacent to the insertion zone, and a bag opening device at said position, said device being adapted to open the mouth of the bag while a record is fed therein.

30 7. A machine as claimed in claim 5, including means for maintaining a stack of bagged records adjacent to the insertion zone to constitute a buffer store.

35 8. A machine as claimed in claim 1, in which the uniting device comprises means for applying adhesive to the blanks of one of said series, and means for pressing each blank against the simultaneously-arrived blank of the other series.

40 9. A machine as claimed in claim 8, in which means are provided for folding edge portions of blanks of the first series and the adhesive-applying means is arranged to operate upon blanks of the second series.

45 10. A machine as claimed in claim 8, in which the adhesive-applying means is similar to an off-set printing device and is arranged to apply a pattern of adhesive to blanks of the one series, said pattern corresponding to the form of folded edge portions of each blank of the other series.

50 11. A machine as claimed in claim 1, including a weighing device arranged to receive sleeves in succession as they are produced by operation of the uniting device.

55 12. A machine as claimed in claim 1, including a conveyor arranged to carry blanks in succession past folding means arranged to operate on those edges of each blank which are side edges in relation to the motion of the blanks and another conveyor arranged to receive the blanks after they have passed said folding means and carry said blanks in succession in a direction at right-angles to said one direction past further folding means arranged to operate on the remaining edges of each blank.

60 13. A machine as claimed in claim 1 including means for removing records in succession from a stack and feed said records towards the insertion zone.

65 14. A machine as claimed in claim 13, in which the record feeding means includes suction devices operable repeatedly to remove the uppermost record from said stack, guide means to receive records from said suction devices, said guide means being engageable with the edge of each record at two diametrically opposed positions, and means for causing each record to slide along said guide means.

70 15. A machine as claimed in claim 14, including a metal detecting device mounted adjacent to the path of records sliding along said guide means and rejector means for separating said

guide means at a position adjacent to said metal detecting device, said rejector means being under control of said metal detecting device so that whenever said device detects a metal disc travelling between successive records said guide means are separated to allow said metal disc to drop out of the record path.

16. A machine as claimed in claim 13, in which said record

removing means is arranged to deliver records to means for presenting said records in succession to inspection devices.

17. A machine as claimed in claim 16, including means to maintain a stack of records between said record removing means and said record presenting means to constitute a buffer store.
